UNITED STATES PATENT OFFICE

154,120

DESIGN FOR A LOCOMOTIVE BODY

Donald L. Hadley, Meriden, Carleton B. Ryder,
 Huntington, and Nicholas F. Pedersen, New
 Hartford, Conn., assignors to The Baldwin
 Locomotive Works, Eddystone, Pa., a corpora-
 tion of Pennsylvania

Application September 3, 1947, Serial No. 141,188

Term of patent 3½ years

(Cl. D66—1)

To all whom it may concern:

Be it known that we, Donald L. Hadley, Carleton B. Ryder, and Nicholas F. Pedersen, citizens of the United States and respectively residing at Meriden, Huntington, and New Hartford, in the respective counties of New Haven, Fairfield, and Litchfield, State of Connecticut, have invented a new, original, and ornamental Design for a Locomotive Body, of which the following is a specification, reference being had to the accompanying drawings, forming a part thereof.

In the accompanying drawings—

Figure 1 is a perspective view of a locomotive body embodying our new design;

Fig. 2 is a partial side view of the locomotive body;

Fig. 3 is a partial plan view of the locomotive body; and

Fig. 4 is a front elevation of the locomotive body.

The characteristic features of our design reside in the portions shown by means of full lines in the drawings.

We claim:

The ornamental design for a locomotive body, substantially as shown and described.

DONALD L. HADLEY.
 CARLETON B. RYDER.
 NICHOLAS F. PEDERSEN.
